UNITED STATES PATENT OFFICE

LOUIS A. GEBHARD, OF WASHINGTON, DISTRICT OF COLUMBIA, ASSIGNOR TO WIRED RADIO, INC., OF NEW YORK, N. Y., A CORPORATION OF DELAWARE

NEUTRALIZING SYSTEM FOR RADIO TRANSMITTERS

Application filed December 22, 1928. Serial No. 327,989.

My invention relates to neutralizing systems in general and more specifically to a method and system for neutralizing transmitting systems of the type employing thermionic tubes.

3 An object of my invention is to provide a system by which radio transmitters employing thermionic tubes may be readily and easily neutralized.

10 Another object of my invention is to provide a method for neutralizing the thermionic tubes and associated circuits of a high frequency transmitter.

15 Still another object of my invention is to provide a system for neutralizing thermionic tube circuits in a high frequency transmitter whereby the correct potentials supplied the several circuits are automatically regulated by the neutralizing system.

20 Other and further objects reside in the arrangement of the transmitter system and the neutralizing system employed therewith, a better understanding of which can be had by referring to the specification following

25 and to the accompanying drawings, wherein:

Figures 1 and 2 are diagrammatic illustrations showing the transmitting system and the neutralizing system of my invention and Figs. 3 and 4 are schematic circuit diagrams showing the transmitting system and the neutralizing system of my invention.

30 In high frequency transmitters in general the several parts are usually electrically shielded each from the other. In such transmitters employing thermionic tubes and associated input circuits, output circuits, and energy supply circuits, the shielding is necessary to prevent interference between the several circuits. It is necessary to neutralize the several thermionic tube circuits and provide the proper balance of the inter-related circuits. In transmitters where each individual thermionic tube is shielded in respect to the other and where the transmitter in its 35 entirety is so shielded, it is often difficult to determine the balanced condition. The removal of the shielding from a section of the transmitter causes an unbalanced condition which when corrected with the shielding removed will be unbalanced when the shield-

ing is replaced. The neutralization may be most conveniently accomplished by connecting to the input and output circuit a condenser the capacity of which can be varied to counter-balance the capacity of the inter-related electrodes and associated circuit constants. The balanced condition is usually observed by noticing an improvement in the overall efficiency of the transmitter, which is only an indirect indication of the neutralized condition. To employ individual means associated with the respective thermionic tubes and their associated circuits, affords a more accurate means for determining the condition of balance. This method, however, introduces certain difficulties including the first mentioned inconvenience of removing the shielding and the loss caused by the indicating means and possible damage thereto from high frequency energy. The neutralizing system of my invention avoids the foregoing difficulties and affords an efficient and accurate means for determination of the balanced condition.

Fig. 1 of the accompanying drawings shows two units 1 and 1a of a radio transmitter in partial cross-section. Inductances 2 and 2a are included in units 1 and 1a respectively and comprises portions of the high frequency circuits associated with individual thermionic tubes. Inductances 6 and 6a are associated with inductances 2 and 2a respectively whereby high frequency energy will be transferred between inductance 2 and inductance 6 and between inductance 2a and inductance 6a. The terminals of inductance 6 are connected to contact members 7a. The terminals of inductance 6a are connected to contact members 7ab. Contact members 7a and 7ab are adapted to receive suitable contacting members associated with an indicating device and are electrically insulated each from the other and insulated from the metal shielding of the respective units. Fig. 2 is a diagrammatic illustration showing the indicating device employed in the neutralizing system and method of my invention. The indicating device in its entirety may be enclosed in a suitable container 10a which may be of metal or of suitable insulating composi-

tion. The indicating device comprises contacting members 7, capacity 8, indicating meter 9 and container 10a. The several constituent units are interconnected as shown in 5 Fig. 3 of the accompanying drawings.

Fig. 3 shows a representative circuit arrangement schematically representing one of the units 1 or 1a of Fig. 1. Thermionic tube 1, having cathode 18, control electrode 19 and anode electrodes 20 is associated with suitable energy supply circuits and high frequency circuits. The input circuit of thermionic tube 1 comprises inductance 2a and capacity 16 interconnecting cathode 18 and control electrode 19. Inductance 2a is associated with source of high frequency energy 27 which may comprise a suitable thermionic tube system. The frequency characteristics of inductance 2a may be suitably adjusted 10 by means of capacity 13. Capacity 16 serves as a high frequency circuit for high frequency energy without providing a low resistance across source of control electrode biasing potential 14. Cathode 18 is energized by source 15 and anode 20 by source 17. The output circuit associated with thermionic tube 1 comprises inductance 2 and capacity 4. Capacity 4 prevents short-circuiting of 15 source 17 through inductance 2. The frequency characteristics of inductance 2 may be suitably adjusted by means of variable capacity 3. A load circuit 5 is associated with inductance 2 and may comprise the input circuit of a thermionic tube amplifier, a wired radio circuit or a space radio radiating system as shown. Capacity 11 is associated with inductance 2a and anode 20. Adjustments of capacity 11 provide different conditions 20 of balance between anode 20, cathode 18, control electrode 19 and the respective associated circuits. Inductance 6 is associated with inductance 2 whereby high frequency energy 25 may be transferred thereto. Indicating device 10 comprising contacting members 7, meter 9 and variable condenser 8 is adjustably positioned in respect to contact members 7a. Inductance 6a is positioned in inductive relation to inductance 2a and is electrically connected to contact members 7a. 30 The operation of the transmitting system and method for neutralizing the system, schematically illustrated in Fig. 3, is as follows: Sources 14, 15 and 27 are connected to thermionic tube 1 and associated circuits. 35 Source of anode potential 17 is not connected to the tube at this time. Input circuit 2a, 13 is adjusted to resonant frequency. Balance condenser 11 is adjusted to some value believed to be near that required for balanced. 40 Output circuit 2, 3 is adjusted to a frequency which is approximately the resonant frequency. Indicating device 10 is adjusted to a frequency value differing from the above mentioned resonant frequency. Indicating device 10 is now connected with inductance 45

6 and the capacity value of condenser 8 adjusted to a value whereby frequency characteristics of the circuit 6, 9, 8 approach the resonant frequency. Meter 9 will have a maximum deflection when circuits 2a—13 and 2—3 have approximately the same frequency characteristics. Condenser 11 is now adjusted to a value whereby the indicated reading of meter 9 is reduced. If this reading is of too low a value condenser 8 70 may be adjusted so that the circuit 6, 8 and 9 will have frequency characteristics more nearly corresponding to the high frequency energy. The frequency characteristics of circuits 2a, 13 and 2, 3 are now adjusted to 75 the proper values. This process of adjustments is repeated until the proper adjustments are obtained, at which time an increase or a decrease in the capacity value of condenser 11 causes a corresponding increase 80 in the reading of meter 9.

Fig. 4 is a schematic circuit diagram showing the neutralizing system for radio transmitters of my invention. Thermionic tubes 1, 1a, 1b and 1c are employed in suitable amplifier circuit arrangements associated with source of high frequency energy 27. Thermionic tubes 1, 1a, 1b and 1c are illustrated as of the three-electrode type, however, it is obvious that thermionic tubes employing four or more electrodes may be employed. Thermionic tube 1 is energized from sources 14, 15 and 17; thermionic tube 1a is energized from sources 14a, 15a and 17; thermionic tube 1b is energized from sources 14b, 15b and 17, and thermionic tube 1c is energized from sources 14c, 15c and 17. Load circuit 5 is associated with inductance 2 and may comprise the input circuit of a thermionic tube, a wired radio system or a space radio radiating system as shown. The individual thermionic tubes and associated input and output circuits are balanced by means of condensers 11, 11a, 11b and 11c. The frequency characteristics of the input and output circuits are controlled by means of inductances 2, 2a, 2b and 2c and capacities 3, 3a, 3b and 3c respectively. The supply of anode potential to thermionic tubes 1, 1a, 1b and 1c is controlled by individual relays 21—22, 21a—22a, 21b—22b and 21c—22c, respectively. Source 25 supplies the necessary energy for actuating electro-magnets 21, 21a, 21b and 21c by means of contacts 24. Contacts 24 are engaged by means of electromagnet 23 which is energized from source 25 by momentary contact switch 26. Fig. 4 shows the indicating device comprising condenser 8, meter 9 and contacting members 7a and inductance 6a. Auxiliary contact members 12 are opened by the engagement of members 7 and 7a thereby interrupting the anode supply circuit of thermionic tube 1a. Contact members 12 are insulated 100 from contact members 7a but are mechan- 105 110 115 120 125 130

ically connected thereto by suitable insulating members. Contacting members 7 and associated circuit 8-9 are adapted to be connected to contact members 7ab. The latter position causes contact members 12a to open which deenergizes electromagnets 21a and 21b. The deenergization of electromagnet 21b allows contact members 22b to open thereby deenergizing the anode circuit of thermionic tube 1b. Similarly contact members 7 may be caused to engage with contact members 7abc which would cause contact members 12b to open. Electromagnet 21c would be deenergized which would allow contact members 22c to open and cause the deenergization of the anode circuit associated with thermionic tube 1c. Electromagnets 21a and 21b are also deenergized.

The method of neutralizing or balancing the transmitting system of my invention is schematically illustrated in Fig. 4. The indicating device comprising contacting members 7, variable condenser 8 and meter 9 is engaged with contact members 7a. The anode potential supply to thermionic tube 1a is simultaneously and automatically removed. Circuit 2b-3b is adjusted to resonant frequency. Balance condenser 11a is adjusted to some value believed to be near that required for balance. Circuit 2a-3a is adjusted to a frequency which is approximately that of the resonant frequency. Circuit 6a-7-8-9 is adjusted to a frequency value differing from the above mentioned resonant frequency and later adjusted to a frequency value more closely corresponding to the resonant frequency. Meter 9 will have a maximum deflection when circuit 2a-3a and 2b-3b have approximately the same frequency characteristics. Balancing condenser 11a is now adjusted to a value whereby the indicated reading of meter 9 is reduced. If this reading is of too low a value, condenser 8 may be adjusted so that the circuit 6a-7-8-9 will have frequency characteristics more nearly corresponding to the high frequency energy. The frequency characteristics of circuits 2a-3a and 2b-3b are now adjusted to the proper values. This process is repeated with each of the circuits associated with thermionic tubes 1b and 1c and in each instance the adjustments are continued until an increase or decrease of capacities 11a, 11b or 11c causes an increase in the reading of meter 9 when associated with the respective circuits. The anode potential is automatically removed from the succeeding thermionic tube amplifier circuits when adjustments at the particular time are being made.

The method and system for neutralizing or balancing radio transmitters of my invention offers many advantages. No part of the transmitter need be removed during the process of neutralizing. The state of bal-

ance may be readily determined by the attending operator and may be corrected without undue delay and complicated procedure by his merely inserting the indicating device in the plug receptacles exposed in the various transmitter panels or connected to the various circuits. Suitable contact members may be associated with such plug receptacles whereby an artificial circuit is connected to the respective energy pick-up coils when the indicating device is not inserted in that particular circuit at the time.

I realize that many modifications of my invention are possible without departing from the spirit of my invention and it is to be understood that my invention shall not be limited to the accompanying drawings or the foregoing specification but only by the scope of the appended claims.

What I claim as new and desire to secure by Letters Patent of the United States is as follows:

1. A method for neutralizing radio transmitters employing a multiplicity of coupled thermionic tube circuits comprising the steps of adjusting the frequency characteristics of the input circuit of a selected tube, simultaneously deenergizing the anode supply circuit of the selected tube, connecting a circuit to said input or output circuit for determining the relative energy therein, adjusting the frequency characteristics of the input and output circuits to obtain a maximum indication of energy, adjusting the relative capacity between said input and output circuits to obtain a relatively minimum value of energy in said output circuit restoring the anode supply circuit and repeating the above mentioned steps with each of said multiplicity of coupled thermionic tubes.

2. A method for neutralizing radio transmitters employing a multiplicity of coupled thermionic tube circuits comprising the steps of adjusting the frequency characteristics of the input circuit of a selected tube, simultaneously deenergizing the anode supply circuit of the selected tube while maintaining the cathode circuit in energized condition, determining the relative energy in the output circuit, adjusting the frequency characteristics of the input and output circuits to obtain a maximum indication of energy, adjusting the relative electrode capacity of said thermionic tube to obtain a relatively minimum value of energy in said output circuit restoring the anode supply circuit and repeating the above mentioned steps with each of said thermionic tubes.

3. A neutralizing system for signaling systems employing thermionic tubes comprising in combination input circuits, output circuits, a balancing condenser common to said circuits, an inductance adjacent to one of said circuits, said inductance being provided

- with contacting members, an indicating device comprising a meter and an adjustable capacity and means for connecting said indicating device with said contacting members.
5. A method for neutralizing radio transmitters employing a multiplicity of thermionic tube circuits comprising the steps of adjusting the frequency characteristics of the input circuit, simultaneously deenergizing the anode supply circuit while maintaining the cathode circuit in energized condition, determining the relative energy in the output circuit, adjusting the frequency characteristics of the input and output circuits 10 to obtain a maximum indication of energy, balancing the relative electrode capacity of said thermionic tube to obtain a relatively minimum value of energy in said output circuit, restoring the anode supply to said thermionic tube and repeating the above mentioned steps with each of said thermionic tubes.
15. 6. A method for neutralizing radio transmitters employing a multiplicity of thermionic tube circuits comprising the steps of adjusting the frequency characteristics of the input circuit of a selected thermionic tube circuit, simultaneously reducing the anode to substantially zero potential for the selected thermionic tube, determining the relative energy in the output circuit, adjusting the frequency characteristics of the input and output circuits to obtain a maximum indication of energy, electrically balancing the relative electrode capacity of said thermionic tube to obtain a relatively minimum value of energy in said output circuit, restoring the anode supply to said tube and repeating the above mentioned steps with each 20 of said multiplicity of thermionic tubes in succession.
25. 7. A neutralizing system for transmitters employing thermionic tubes comprising in combination a plurality of high frequency output circuits associated with said thermionic tubes, a plurality of inductances associated with said output circuits, a plurality of contact members associated with said inductances and an adjustable capacity electrically connected with an indicating device, said capacity and indicating device being connectable with said first mentioned contact members.
30. 8. A neutralizing system for thermionic tube high frequency transmitters comprising in combination input and output circuits, an auxiliary inductance circuit associated therewith, plate circuit potential supply means for said output circuits, said auxiliary inductance circuit being provided with contacting members adapted to receive other contacting members connected with an energy indicating device and an adjustable capacity and means for interrupting the connection of 35
- said plate circuit potential supply means in the particular output circuit with which said indicating device is selectively connected.
9. A neutralizing system for thermionic tube high frequency transmitters comprising in combination a plurality of auxiliary inductances associated with the high frequency circuits of said thermionic tubes, circuits for supplying plate potential to said tubes, and an indicating circuit comprising a meter and an adjustable capacity adapted to be connected with either of said auxiliary inductances, while automatically disconnecting the plate potential supply to the particular tube to which said last mentioned auxiliary inductances are connected.
10. 10. In a neutralizing system for radio transmitters employing thermionic tubes the combination of auxiliary inductances associated with the high frequency circuits of said tubes, power supply means for the plate circuits of said tubes, said inductances being electrically connected to individual groups of contact members and an indicating apparatus comprising energy indicating means and an adjustable capacity adapted to be selectively connected with said individual groups of contact members, while automatically disconnecting said power supply means from the plate circuit of one of said tubes.
15. 11. In a neutralizing system for radio transmitters employing thermionic tubes the combination of auxiliary inductances associated with the high frequency circuits of said tubes, energy supply circuits for said thermionic tubes, said inductances being electrically connected to individual groups of contact members, and an indicating apparatus comprising energy indicating means and an adjustable capacity adapted to be selectively associated with said individual groups of contact members, said groups of contact members being mechanically associated with other contact members adapted to control the energy supply circuits to the above mentioned thermionic tubes when said indicating apparatus is associated with said first mentioned contact members.
